UNITED STATES PATENT OFFICE.

HORACE P. BROWN, OF OAKLAND, CALIFORNIA, ASSIGNOR TO PACIFIC BURT COMPANY, LIMITED, OF TORONTO, ONTARIO, CANADA, A CORPORATION OF ONTARIO.

CONTINUOUS-INTERFOLD PACKET.

Application filed July 22, 1925. Serial No. 45,188.

This invention relates to record supplies for use in making manifold inscriptions, and with respect to its more specific features, to a record supply packet wherein the record strips are separate from each other and of such length that a large number of printed forms, subsequently to be filled in, may be printed thereon, and successively drawn or fed to position for inscription, as for instance, to inscribing position in a typewriting machine or the like, succeeding forms being drawn from the packet to inscribing position in the machine by drawing the forward portions of the strips.

One of the main objects of the invention is the provision of a practical and efficient record supply packet of the character referred to, by use of which it will be unnecessary for the operator to perform carbon interleaving operations between inscribing operations on successive forms, or to use carbons independent of the packet, and in which a great length of a separate carbon strip may be employed and its whole length utilized by the successive drawing operations without injuring the carbon strip or placing on any part of the length of the carbon strip drawing tension sufficient to part the carbon strip, the packet also being so constructed that any of the carbon strips or any portion of the length of any number of carbon strips that may be used is readily accessible and may be conveniently adjusted and manipulated relative to the record strips without dismembering the packet.

By the present invention there is provided a packet for use in typewriting machines which is instantly available for making a succession of manifold copies, as for pay-roll checks, letterheads, purchase orders, invoices, bills of lading, and the like, all without the use of carbons other than that contained in the packet itself. The packet consists of a plurality of strips of paper, one strip being an original and having successive forms printed thereon, and the other strip or strips serving as records or duplicates therefor. The strips are superposed one on the other and folded in zig-zag formation to form a packet which will readily unfold as the strips are fed as a continuous composite web through a typewriting machine, where the printed forms are filled in.

As will be perceived further on, there is provided a continuous strip of carbon paper

which is separated from the record strips and which is interposed between the original and the duplicate record strips and interfolded therewith so as to be retained between the record strips and to be advanced therewith to inscribing position, and so as always to lie in position such that a record of the typing or filled-in matter will be transferred to the duplicates during the typing operation.

For the purpose of more clearly describing the invention, reference is made to the accompanying drawing forming a part of this specification and drawings, in which—

Fig. 1 is a perspective view of a packet.

Fig. 2 is a plan view of the duplicate strip.

Fig. 3 is a plan view of the carbon strip.

Referring to the drawings in detail and particularly to Fig. 1, A indicates in general a packet consisting of a plurality of separate, continuous strips of paper such as indicated at B, C, and D. These strips are superposed one on the other as shown and are folded in zig-zag fashion along the lines indicated at 2 and 3 so that a packet formation is obtained. The uppermost record strip indicated at B will be the original strip, the strip C the transfer-strip, or strip of carbon paper, and the sheet D the duplicate strip.

The original strip B has a longitudinal series of forms printed thereon as shown; such as check blanks, letter heads, or whatever the case may be, as indicated at 4, and the blank spaces are preferably filled in by passing the strips as a composite continuous web through a typewriting machine. For instance, if pay roll checks 4 are to be filled out, three or more checks may be printed on each fold in successive order as indicated in Fig. 1. The checks are filled out during the typing operation and a transfer is made, by the carbon paper, on the duplicate strip indicated at D. The original strip B is perforated along the lines 5 to weaken the same and to permit the checks to be easily separated or torn apart and the duplicate is similarly perforated along the lines 6 to permit the duplicates similarly to be separated from each other if desired. The several strips are also similarly weakened as by being perforated along the parallel lines of transverse fold indicated at 2 and 3, and the strips may thus first be separated in sheet

sections and then later separated into individual checks and duplicates if desired. The original strip and the duplicate may thus have two sets of perforations, those indicated at 2 and 3 and the intermediate perforations shown at 5. The carbon strip C is, however, only perforated along the lines 2 and 3 (see Fig. 3) and thus the carbon sheet sections or folds may after use in the packet, 10 be used for other work whenever desired.

The two separate record strips B and D, and the third, or transfer strip C, continuously extend from the packet to the platen of the typewriting machine, lower folds of 15 the packet being drawn to the platen by successively drawing upper folds of the packet to writing position. It will be seen that the plurality of zig-zag folds of the transfer strip C lie in the packet in interengaging or 20 interfolded relation to those of the record strips, so that the lower folds of the three strips are retained against movement relative to each other, while upper folds thereof are being drawn to writing position in the 25 machine. By the restraint against resultant relative movement, defacement on account of smutting of the record strip by the carbon strip is largely avoided and, it will be noted, the restraint against relative movement increases 30 the deeper the folds are located in the packet, on account of the increased weight of packet material above. The number of folds of the packet may be as many as desired, there being practically no limit 35 to the length of strip which may be employed. It will be noted, however, that although the carbon strips may be very long, all the drawing strain on the carbon strip is confined to the relatively short length running 40 from the upper fold of the packet to the platen of the typewriter, the lower folds of the carbon strip being entirely free of the drawing strain. Hence, by the construction described, even though the transfer 45 strip be very weak, an even though the transfer material thereon readily may come off, the arrangement of the transfer strip in the packet largely provides against smutting of the record strips and permits the employment 50 of a very long, continuous transfer strip between and in manifold contact with the record strips, and the consumption of its entire length by the successive drawing operations, whereas the strain on the strip 55 due to the successive drawing operations may be relatively light and much lighter than would be required to advance the weight of the whole length of transfer strip at each of the successive drawing operations. 60 As no one strip is directly connected to another, they may readily be separated for examination, adjustment and the like, at any point in the packet. Should the relatively weaker transfer strip be accidentally divided 65 at any point in the packet, the parted sec-

tion will be retained in place and will be advanced by the advance of the encompassing record strips. As all the fold lines of the strips are parallel to each other and at right angles to the direction of feed movement, the 70 interfolding has no tendency laterally to displace the transfer strip relative to the record strips.

The longitudinal side edges of the strips are free and are open to inspection at each 75 side of the packet. As the transfer strip is of a dark color its position throughout the packet may readily be traced. Should it be out of registry the packet may be opened up at the precise point and the carbon sheet adjusted in either lateral direction required. As the lines of fold in the packet are all 80 parallel to each other, the carbon strip runs free from the packet to writing position and there is practically no chance for it to become 85 entangled and torn as it feeds from the packet, notwithstanding it may be of great length.

A packet of this character is exceedingly useful when filling out pay roll checks, bills 90 of lading, invoices, and the like, as the original, the carbon, and the duplicate are fed by the operator as a composite continuous web through the typewriter as the checks or other work are filled in. This is obviously 95 an advantage as it eliminates the necessity, on the part of the operator, of inserting separate sheets and the carbon and aligning the same for each operation. The inserted continuous carbon strip is also a 100 time saver and important as it eliminates the necessity of re-inserting a carbon sheet for each successive manifold set of forms. It should also be noted that when the originals and duplicates are separated along the fold 105 lines a by-product is obtained; to-wit, the carbon sheets, which may be re-used for other purposes whenever desired. The user of a packet of this character thus has all the carbon paper required for the filling in 110 of the packet and obtains as a by-product a number of carbon sheets to take care of other work.

Having thus described my invention, what I claim and desire to secure by Letters Patent is—

1. A packet for use in making manifold inscription having, in combination, two long, continuous, separate, relatively superposed, runner record-strips, a third long, continuous, separate, runner transfer-strip of carbon paper between and in manifold contact with said record-strips, and means, including a plurality of zig-zag folds of each of said strips, lying in the packet, coactive to retain lower folds of said transfer strip from movement relative to lower folds of said record strips and free of drawing strain consequent from drawing upper folds of said transfer-strip from the packet. 130

2. A packet for use in making manifold inscription having, in combination, two long, continuous, separate, relatively superposed, runner record-strips of paper, one being the original and the other the duplicate, a third long, continuous, separate runner transfer-strip of carbon paper between and in contact with said record-strips, and means, including a plurality of zig-zag folds of each of said strips, lying in the packet, coercive to retain lower folds of said transfer-strip from movement relative to lower folds of said record-strips and free of drawing strain consequent from drawing upper folds of said transfer-strip from the packet, the original record-strip having a longitudinal series of printed forms, each of said strips being weakened along its lines of fold, all fold lines of said strips being parallel to each other and at right angles to the direction of said drawing.

3. A packet for use in making manifold inscription having, in combination, two long,

continuous, separate, relatively superposed, runner record-strips of paper, one being the original and the other the duplicate, a third long, continuous, separate runner transfer-strip of carbon paper between and in contact with said record-strips, and means, including a plurality of zig-zag folds of each of said strips, lying in the packet, coercive to retain lower folds of said transfer-strip from movement relative to lower folds of said record-strips and free of drawing strain consequent from drawing upper folds of said transfer-strip from the packet, the original record-strip having a longitudinal series of printed forms, each of said strips being weakened along its lines of fold, all fold lines of said strips being parallel to each other and at right angles to the direction of said drawing, the longitudinal side edges of each of said strips being free and unconnected to another of said strips.
